HIGH-POWER ELECTRON GENERATING
DEVICE

Joseph Béthenod, Paris, France

Application June 2, 1923, Serial No. 642,946, and
in France June 15, 1922

13 Claims. (Cl. 250—27.5)

At the present time there is being used in electronics, and more particularly in wireless work, a type of apparatus adapted to electron emission permitting more especially either the rectification of alternating currents of any given frequency, or else the production of alternating currents of likewise arbitrary frequency, from a direct current of high voltage.

All of these apparatus, as a matter of principle, comprise a cathode raised to a more or less high temperature, whose surface is the seat and source of electron emission and generation and thus constituting, as is well known, the basis underlying the operation in question. When an apparatus of high power is to be built, one encounters the following difficulty:

To raise the cathode to the requisite temperature, this electrode is ordinarily given the shape of a filament heated by means of an auxiliary source of current; now, the number of electrons emanating per square centimeter surface area of the cathode per unit of time (second) depends only upon the absolute temperature thereof, and if it shall not attain a temperature liable to cause rapid destruction of the device, it is necessary to make the cathode of large surface to the end of realizing correspondingly large power. It is quite evident that the filamentary form is badly adapted to the purpose in question, and that it would be far preferable if ways and means were known to give the cathode the construction of a plate of any convenient cross-sectional shape, disc or cylinder especially.

However, then the direct electric heating of the cathode would become an impossibility, for obvious reasons, so that it is necessary to discover another method of heating. Reasoning along these lines, the proposition has been made to give the anode and the cathode the form of two concentric cylinders, with the anode being arranged exteriorly, to heat the cathode by virtue and means of radiation, more particularly by the aid of a spiral disposed interiorly thereof and raised itself to incandescence by means of an auxiliary source of current. However, such an artifice would give only a rather limited improvement if proceeding along the lines stated, because it is known that the realization of a heating spiral or coil, if it shall be of great power and effect, will always be a delicate problem to solve.

Now, in conformity with the present invention heating of the cathode is accomplishable by forming it of a circular body, as a matter of principle, and so giving it an annular or circular shape, and in which currents are induced by the aid of an alternating magnetic flux conveniently arranged. The Joule effect thus produced in the very body constituting the cathode suffices for raising it to the desired temperature.

By way of example, Figs. 1 and 2 herewith in-

dicate diagrammatically a number of embodiments of the invention that are particularly simple in nature. Fig. 3 is a cross-section taken through the center of Fig. 1, and Fig. 4 is a cross-section taken through the center of Fig. 2.

65

According to Fig. 1, the device consists essentially of a container or vessel 1 made of glass or of quartz preferably, possessing the shape of a torus. In the interior thereof are arranged:

A cylindrical plate 2 forming the cathode to be heated, this plate being made from a convenient kind of metal lined or covered, if so desired, with metallic oxides (oxide of barium, etc.) to the end of enhancing electron emission.

Further, a second cylindrical plate 3 constituting the anode, and consisting, for instance, of a thin tungsten sheet or strip.

Finally, optionally, a third plate perforated by holes and disposed between the two chief electrodes 2 and 3, this latter, optionally provided, plate constituting the control electrode or grid well known in the art, the useful function of which has been demonstrated in certain services and applications, especially the production of alternating currents of any frequency at all, from direct current of high voltage.

85

Traversing from one end to the other of the torus-shaped container 1, there is arranged a closed magnetic circuit 5 built up of laminated iron, and through which passes an alternating magnetic flux created, e. g., by means of a winding 6 energized by an alternating current derived from any convenient source at all. Under these conditions, cathode 2 which forms a closed turn, thus constitutes the secondary circuit of a transformer, of which 6 is the primary winding. By appropriately dimensioning the various constitutive elements of the device, it is feasible to raise the said cathode to the desired temperature quite easily merely by Joule effect. It must be noted, however, that anode 3 and optional control 4 must be provided with slits 7 directed towards the generatrix of the respective cylinders, to the end of limiting the Joule effect produced by 5 in the cathode 2.

95

Moreover, according to the effect to be produced, the medium inside enclosure or vessel 1 can be chosen ad libitum; indeed, one can choose a vacuum as high as feasible, or one may, on the contrary, choose as such medium any convenient kind of gas, argon, or the like. Finally, as regards the constitution of the magnetic circuit 5 and the position of inductor winding 6, recourse may be had to various forms of construction; for instance, magnetic circuit 5 may be that of a voltage transformer, for feeding the circuit containing electrodes 2 and 3. It will be noted that for the sake of greater clearness and simplicity, the tapping or connecting points for the currents corresponding to the various electrodes are not 115

105

120

- being shown in the illustration since they do not represent any particular features in this case. Furthermore, anode 3 may be constituted, if so desired, by a coil possessing very closely wound turns the inside of which is subject to the circulation of a convenient kind of cooling liquid, or the like. As to the rest the entire apparatus could be plunged and immersed in a vat filled with oil or an analogous liquid.
10. In Fig. 2 the electrodes possess the shape of flat rings; there being shown but a part of the magnetic circuit 5, and it has been supposed by way of modification that the apparatus comprises no control electrode (or grid), cathode 2 being in this case shown as being surrounded by two anodes 3, 3, in such a manner that its whole surface is rationally utilized for the purpose of electron emission. The said two anodes are equipped, if necessary, with radial slits or grooves 15 in accordance with what has been pointed out before in connection with Fig. 1. It goes moreover without saying that whatever applies with regard to Fig. 1 is likewise adaptable to Fig. 2, and contrariwise. More precisely speaking, in an arrangement as illustrated there could also be used two anodes (and, if deemed advisable, also two grids) for each cathode, while in an arrangement as depicted in Fig. 2, but one anode may be provided, and also additional control electrodes 20 (grids) may be furnished, and so on.
- Both of the arrangements hereinbefore referred to are only given by way of example, and they are capable of numerous variations and modifications by anybody experienced in the art. For example, 25 magnetic circuit 5 may be only partly closed, especially when the frequency of the induced current flowing through 6 has a high value.
- Having described my invention, what I claim is:
1. In a thermionic device the combination of a sealed container in the shape of a torus having therein a plurality of annular electrodes, and a magnetic core extending through the opening of said torus and having thereon a winding arranged in inductive relation to said electrodes and adapted to be traversed by fluctuating currents whereby one or more of said electrodes may be heated by induction.
  2. In a thermionic device the combination of a sealed annular container, cylindrical cathode and plate electrodes concentrically disposed and in spaced relation to each other and to said container, a magnetic core extending through the opening of said container and in inductive relation to said electrodes, and means on said core to generate a varying magnetic field whereby one of said electrodes is heated by induction.
  3. In a thermionic device the combination of a sealed container in the form of a torus, a plurality of concentric cylindrical electrodes therein, and a magnetic core arranged in the opening in said torus in inductive relation to said electrodes and having a winding thereon, whereby when said winding is traversed by fluctuating current at least one of said electrodes will be heated by induction, another of said electrodes containing slits to prevent it from being heated by the action of said magnetic core.
  4. In a thermionic device, the combination of an annular sealed container having a plurality of annular electrodes therein, and means comprising a member extending through the opening of said annular container and cooperating with said container and one of said electrodes to heat the said electrode.
5. In a thermionic device, the combination of an annular sealed container having a plurality of electrodes therein, a transformer core extending through the opening of said annular container, and a coil serving as the primary and the electrode to be heated serving as the secondary of the transformer, whereby said electrode may be heated by induction.
6. In a hot-cathode electron-discharge device, an anode, a cathode, an auxiliary electrode for controlling the flow of electrons in the discharge space between said cathode and anode, means for heating said cathode to a temperature of electron emission, said means producing a fluctuating magnetic field adjacent to said cathode, and a magnetic screen substantially preventing said flux from interfering with the electron discharge between said cathode and anode.
7. In a hot-cathode electron-discharge device, an anode, a cathode, an auxiliary electrode for controlling the electron flow in the discharge space between said cathode and anode, and means for producing a magnetic flux for inductively heating said cathode, said means comprising a core of magnetic material inductively interlinked with the heating-current-flow paths in said cathode.
8. In a hot-cathode electron-discharge device, means for inducing a magnetic flux, a cathode member constituting a closed current path inter-linked with the flux induced by said means, an anode co-operating with said cathode, and means for segregating the major portion of the flux interlinked with said cathode from the electron-discharge space between said cathode and anode.
9. In an electron-discharge device, a pair of annular electrodes constituting an electron-discharge space, a hermetic envelope enclosing said discharge space, and means for producing a magnetic flux, all of the flux produced by said means being interlinked with both of said electrodes.
10. In a hot-cathode electron-discharge tube, an anode, a cathode, and a magnetic transformer core associated with said cathode to induce therein currents for heating the same, said magnetic core constituting a low-reluctance flux path segregating the inducing flux from the discharge space between said cathode and anode.
11. In an electron-discharge device, a pair of electrodes constituting an electron-discharge path, one of said electrodes comprising a substantially closed-circuited secondary transformer winding, and a magnetic core constituting a substantially closed-circuited magnetic flux path interlinked with said winding.
12. A hot-cathode device comprising a toroidal container, an annular anode concentrically disposed in said container, an annular cathode similarly disposed within said container, a laminated iron core passing through the central opening of said toroidal container, and a coil for inducing an alternating flux in said core, said cathode constituting a closed-circuited winding surrounding said core.
13. In a thermionic device, a cylindrical cathode, a heating device therefor, and an evacuated envelope electrically separating the heating device from the cathode, the heating device being external to said envelope whereby the heating device is readily replaceable.

JOSEPH BETHENOD.
